DEFENSIVE PUBLICATION

UNITED STATES PATENT OFFICE

Published at the request of the applicant or owner in accordance with the Notice of Apr. 11, 1968, 849 O.G. 1221. Identification is by serial number of the application and the heading indicates the number of pages of specification, including claims, and of sheets of drawing contained in the application as originally filed. The file of this application is available to the public for inspection; reproduction may be purchased for 80 cents per sheet.

Applications published under the Defensive Publication Program have not been examined as to the merits of alleged invention. The Patent Office makes no assertion as to the novelty of the disclosed subject matter.

1 Sheet Drawing. 15 Pages Specification

Rapid build-up of a linear prepolymer (for example, polyester, polyamide, etc.) is accomplished by a new process using novel apparatus, said process comprising the solid phase polymerization of a fluidized bed of prepolymer in a cylindrical vessel having an inverted non-porous cone at its bottom, said cone being attached to the vessel by a porous ring through which a fluidizing gas (for example, nitrogen, etc.) is introduced.
